(57) CLAIM

The ornamental design for a tongue cleaner apparatus, as shown and described.

DESCRIPTION

FIG. 1 is a front, top, and left perspective view of the tongue cleaner apparatus;

FIG. 2 is a front elevational view of the tongue cleaner apparatus;

FIG. 3 is a rear elevational view of the tongue cleaner apparatus;

FIG. 4 is a left side elevational view of the tongue cleaner apparatus;

FIG. 5 is a right side elevational view of the tongue cleaner apparatus;

FIG. 6 is a top elevational view of the tongue cleaner apparatus; and,

FIG. 7 is a bottom elevational view of the tongue cleaner apparatus.

The coiled lines of uneven length covering the upper part of the tongue cleaner apparatus demonstrate a contrast in appearance from the lower part of the tongue cleaner apparatus.
